UNITED STATES PATENT OFFICE.

REGINALD PELHAM BOLTON, OF PELHAMVILLE, NEW YORK.

POWER, HEATING, AND VENTILATING APPARATUS FOR BUILDINGS.

SPECIFICATION forming part of Letters Patent No. 576,718, dated February 9, 1897.

Application filed August 29, 1895. Serial No. 560,846. (No model.)

To all whom it may concern:

Be it known that I, REGINALD PELHAM BOLTON, a citizen of the United States, and a resident of Pelhamville, in the county of 5 Westchester and State of New York, have invented certain new and useful Improvements in Power, Heating, and Ventilating Apparatus for Buildings, of which the following is a specification.

10 My invention consists of improvements in power, heating, and ventilating service apparatus for buildings whereby economy is effected in condensing the steam and in feeding the boiler of the power apparatus, also in 15 heating the building by hot air when heating is required, and also in ventilating the building, as hereinafter described, reference being made to the accompanying drawings, in which—

20 Figure 1 is a sectional elevation of a building provided with service apparatus in accordance with my invention. Fig. 2 is a sectional elevation of the condensing and heating and ventilating apparatus on an enlarged 25 scale.

25 In Fig. 1, *a* represents the boiler for supplying steam for power, heating, and other purposes, said boiler being located in the basement, as usual, for various economical reasons.

30 *b* represents a motive-engine in which some of the steam-power is employed for operating a dynamo *c* for electric purposes, said engine and dynamo being also located in the basement for certain well-known advantages 35 thereof.

35 *c* represents the steam-exhaust pipe of the engine. It is extended to the top of the building, preferably within chimney *f* of the boiler-furnace. On the roof *g*, or it may be any other suitable elevated support, is a condensing-coil *h*, with which the exhaust-pipe *c* connects for condensing the steam and for utilizing the waste heat of the steam for heating 45 the building in seasons when heat is required.

40 *i* is the discharge-pipe for the water of condensation from the coil. It returns to the basement and connects with the hot-water drum *j*, from which it is caused to feed into 45 the boiler again through pipe *k* by the pressure of the column in return-pipe *i*, which is to be sufficient to overcome the boiler-pres-

sure. An air-chamber *l* in the upper part of the drum *j* is provided for trapping off the air.

m represents a pump connected with the 55 hot-water drum for replenishing the supply of water, as may be required, from time to time.

The return-pipe *i* may connect with the suction of the pump *m* in cases where the boiler-pressure is liable to rise higher than 60 the weight of the returning column of water to utilize the pump to overcome the overbalance of the steam-pressure.

For cooling the condensing-coil I employ a 65 fan-blower, as *n*, in suitable connection with the coil and with a ventilating-flue *o* for withdrawing the air from the different rooms of the building to cool them and blowing it over the exterior of the coil, or by reverse action to force the heated air from the coil into the 70 rooms to heat them when required, said coil being inclosed in a suitable cover *p* for causing the best effects on the coil.

The side wall *q* of the case through which the hot air escapes from the condenser into 75 the atmosphere overhangs or inclines outward from the bottom upward to fend off the rain from the openings, and the openings are provided with deflector-doors *s* in Fig. 2, which, being limited in the extent of their opening to the level plane or thereabout, cast 80 the hot air upward when issuing from them and will be closed by gusts of opposing wind force to prevent back pressure in the ventilator.

85 A valve *t* is provided for admitting air at the top of the condenser-cover when the heated air is to be used for heating the building. For obtaining purer air the deflector-doors will then close by the effect of the suction. The valve *t* has a rod *u*, connected to a crank *v*, for operating it. The crank may be operated by hand or other means. In this example I represent the fan as geared with an electric motor *w* for operating it, the motor being connected with the dynamo *c* by suitable circuit-wires and a starting-box or rheostat *z*. The ventilating-flue *o* is connected with the different rooms by suitable 90 branch ducts *y* for distributed effect.

100 It will be seen that by locating the condenser on the roof in connection with the power apparatus in the basement by the exhaust-steam and return-water pipes, as de-

scribed, feed-water is returned to the boiler without expenditure of power or with but slight power in case of an overbalance of steam-pressure, and with the hot-water drum 5 and air-trap a vacuum is maintained on the exhaust without expenditure of power; and it will also be seen that by the condenser and its operating-fan located on the top of the building and connected with the ventilating-10 ducts material economy is effected in ventilating and heating the rooms.

That it may appear clearly that the apparatus acts as a ventilator and a heater two series of arrows are shown—one series formed 15 of unbroken lines to represent the course of foul air from the apartments, the other series formed of broken lines to indicate the course of the air to the apartments.

I claim—

20 1. In power, heating and ventilating apparatus for buildings, the combination of steam-power apparatus located in the lower part of the building, a condenser located on or in the

upper part of said building, exhaust and return pipe connections of said power apparatus and condenser, the fan-blower for the condenser, the flue and branches communicating between the rooms of the building and the cover of the condenser through the fan and the outlet and inlet for air to the fan, said fan 25 30 being reversible substantially as described.

2. The combination with the condenser, conduits communicating between the apartments and condenser, and the fan, of the cover having the overhanging outlet side and upwardly-35 deflecting doors to the outlet-openings, and also having the inlet-valve admitting air from the top of the cover substantially as described.

Signed at New York city, in the county and State of New York, this 6th day of August, 40 A. D. 1895.

REGINALD PELHAM BOLTON.
